UNITED STATES PATENT OFFICE

154,891

DESIGN FOR A WALL VASE

Robert Weber, Los Angeles, Calif.

Application July 26, 1948, Serial No. 147,774

Term of patent 7 years

(Cl. D29—28)

To all whom it may concern:

Be it known that I, Robert Weber, a citizen of the United States, residing in the city and county of Los Angeles, and State of California, have invented a new, original, and ornamental Design for a Wall Vase, of which the following is a specification, reference being had to the accompanying drawing, forming part thereof.

Fig. 1 is a front elevation of a wall vase, showing my new design.

Fig. 2 is a side elevation.

Fig. 3 is a rear elevation, and

Fig. 4 is a top plan view.

I claim:

The ornamental design for a wall vase, substantially as shown.

ROBERT WEBER.
